LOUIS JOSEPH MOUNTZ, OF RICHMOND, VIRGINIA.

SECRET BALLOT.

1,146,647.

Specification of Letters Patent. Patented July 13, 1915.

Application filed March 6, 1914. Serial No. 822,950.

To all whom it may concern:

Be it known that I, LOCIS J. MOUNTZ, a citizen of the United States, and a resident of Richmond, in the county of Henrico and State of Virginia, have invented a new and Improved Secret Ballot, of which the following is a full, clear, and exact description.

The object of the invention is to provide a new and improved secret ballot arranged to provide the desired secrecy as far as the voter is concerned, to prevent abstraction of the ballot from the ballot box without detection, to provide a space for the voter's name or other mark to be made by the voter, to prevent such name or mark from being read by any person unless a recount is ordered, and to allow ready collating of the ballots in series with a view to readily detect any missing ballots or surreptitiously added ballots. In order to accomplish the desired result use is made of a ballot sheet, comprising a series of connected and singly detachable ballots, and an identification mark extending irregularly across the series of ballots so that the portions of the mark of the individual ballots in the series are different one from the other. Use is also made of an identification space on each ballot for the reception of a mark or marks made by the voter, and a gummed flap adapted to fold over the space to be gummed to the body of the ballot with a view to conceal the said voter's marks, the said space and the said flap being provided with additional means to render the mark invisible even if the ballot is held up to the light.

A practical embodiment of the invention is represented in the accompanying drawings forming a part of this specification, in which similar characters of reference indicate corresponding parts in all the views.

Figure 1 is a plan view of a sheet of connected and singly detachable ballots; Fig. 2 is an enlarged plan view of one of the ballots as received by the voter from the election official; Fig. 3 is a similar view of the same with the parts in position ready for disposition in the ballot box; Fig. 4 is a similar view of the same with the flap open to disclose the secret mark of the voter in case a recount of the ballots is ordered by the proper authorities; Fig. 5 is a cross section of the ballot on the line 5—5 of Fig. 2; Fig. 6 is a similar view of the same on the line 6—6 of Fig. 3; and Fig. 7 is a similar view of the same on the line 7—7 of Fig. 4.

The ballots A are printed in series on sheets of paper or other material. The sheet is provided with rows of perforations B to separate the ballots A one from the other 60 and to allow convenient detachment of the ballots singly from the sheet. The sheet of ballots is provided with an identification mark extending irregularly across the entire sheet and consequently across each of the 65 ballots, so that the identification mark of any one ballot is wholly unlike the identification mark of the remaining ballots, as will be readily understood by reference to Figs 1, 2, 3 and 4. As shown in these 70 figures the identification mark consists of printed marks C, C and water marks C', C' both in the form of undulating lines or bands extending irregularly across the sheet and consequently across each ballot A, so 75 that the lines on one ballot are wholly unlike the lines on any one of the other ballots in the series. The ballots are preferably provided with numbers D and the same number is used for a series of ballots (say 10), so 80 that the ballots after removal from a ballot box can be readily assorted and placed one alongside the other to prevent surreptitious abstraction of ballots from the ballot box or the addition of spurious ballots without detection by the proper officials.

Each ballot A is provided with a heading E for containing the usual legend as to the election, and a main body portion F for the names of candidates or other matter 90 to be voted for. On the lower end of each ballot A is arranged a space G on which the voter can write his name or make other marks thereon, and adjacent this space and integral with the ballot A is a flap H adapted to be folded over the space G to conceal the voter's marks produced in the said space G. The flap H is provided with an outer gummed portion J adapted to be gummed onto the face of the ballot A directly above 100 the space G so as to prevent unauthorized persons from viewing the marks made by the voter in the space G. The face of the flap H is further provided with a band I, preferably of black ink, so that when the flap is closed the band I overlies the voter's mark and consequently the said mark is rendered invisible even if the ballot is held up to the light. In order to further increase the secrecy of the voter's mark, the space G 105 is preferably provided with a background of lines K to prevent reading of the voter's

marks from the reverse side of the ballot when the latter is held up to the light.

The ballot A is detached from the sheet and handed to the voter by the election official, and then the voter provides the body F with the necessary marks to indicate the persons or other matter to be voted for; after which the voter writes into the space G his name or any other desired identification mark, such, for instance, as the number of the tax receipt or the like, and then the voter closes the flap H and fastens the same by the gummed portion J onto the face of the ballot so that the matter written in the space G is completely concealed (see Fig. 3). This ballot is handed to the election official by the voter to be deposited in the ballot box. In case a recount is ordered the flap H can be opened by slitting it along its crease at the bottom of the ballot to allow of turning the flap upward to disclose the marks written by the voter in the space G, thus proving whether the ballot is genuine or not. It will also be noticed that in a recount the ballots in a series can be readily placed one alongside the other so that their marks C and C' register with each other as they did originally on the sheet of ballots, and if any ballot is missing in the series such a fact becomes at once apparent, and likewise if ballots have been substituted the fact is readily discovered.

Having thus described my invention, I claim as new and desire to secure by Letters Patent:

1. A ballot provided with a space for receiving marks of the voter, and a flap on the ballot and adapted to be folded over the said space and secured to the ballot to conceal the voter's mark, the said space and the said flap being provided with concealing means to render the voter's mark invisible.
2. A ballot provided with a space for receiving marks of the voter, and a flap on the ballot and adapted to be folded over the said space and secured to the ballot to conceal the voter's mark, the said flap being provided with a printed band overlying the said voter's mark when the flap is in closed position.
3. A ballot provided with a space for receiving marks of the voter, the said space having a background to render the mark illegible from the reverse side of the ballot and a gummed flap on the ballot adjacent the said space to overlie the latter and to be gummed to the ballot.

In testimony whereof I have signed my name to this specification in the presence of two subscribing witnesses.

LOUIS JOSEPH MOUNTZ.
